(74) *Attorney, Agent, or Firm*—Charles J. Prescott

(57) **CLAIM**

The ornamental design for an LED light therapy device, as shown and described.

DESCRIPTION

FIG. 1 is a perspective view of a multiple head light therapy device showing my new design.

FIG. 2 is an elevation view of one side of FIG. 1.

FIG. 3 is an elevation view of the opposite side of FIG. 1.

FIG. 4 is a left side elevation view of FIG. 1.

FIG. 5 is a right side elevation view of FIG. 1.

FIG. 6 is a top plan view of FIG. 1; and,

FIG. 7 is a bottom plan view of FIG. 1.

The broken lines shown in the drawings represent unclaimed portions of the design and form no part thereof.

1 Claim, 5 Drawing Sheets
